TIPTOE TREADLE CONSTRUCTION FOR STOVE DRAWERS

Truman H. Cline, Newark, Ohio, assignor to Sears,
Roebuck and Co., Chicago, Ill., a corporation
of New York

Application July 1, 1950, Serial No. 171,687

5 Claims. (Cl. 312—319)

1

The present invention relates to steel cabinet work and is concerned more particularly with a foot pedal operated drawer actuating mechanism.

In certain kitchen furniture articles of all metal construction in which utility and storage drawers are provided which are made up of storage compartments and face panels or escutcheons, various modes of drawer operation have been practiced which facilitate convenience and ease of operation. To illustrate there need be mentioned but a few of these methods which include surface and recessed handle pulls, cam and lever drawer ejectors, etc.

In the construction of certain household kitchen furniture articles such as tables, stoves and storage bins a definite style trend is recognized in a direction towards eliminating surface protrusions and recessed finger pulls. In the construction of various hospital fixtures, medical hygiene favoring the elimination of sharp angle crevices has further supported this trend with the ultimate result of creating a need for flush type escutcheon panels that may be simply and expeditiously maintained clean and sanitary by sweeping surface wiping effort. In the standard patterns of kitchen stoves which are constructed and finished in white enamel surface finishes, the elimination of protruding and recessed drawer pulls makes possible a more faithful adherence to these principles of cleanliness and hygiene and the present invention concerns itself with providing a drawer ejecting mechanism which is rugged and simple in its fabrication and construction so that the drawer faces may be formed with a full surface smoothness. In the operation of herein disclosed embodiments of these mechanisms, it is contemplated further that they be so disposed as to lend themselves to be operated by foot motion or toe depression and to be disposed near the lowermost or floor level of the structure for this purpose as well as for the purpose of occupying an out of visual range position with respect to the major aesthetics which constitute a composite front panel.

The principal object of the present invention therefore is one of achieving a drawer ejecting mechanism which is simple to construct and which may be fabricated under conditions of small cost of labor and materials.

A further object of the present invention is to provide a drawer ejecting mechanism which is independent of springs or torsion elements both in direct operating and return movement aspects so as to be free of those detriments that result from wear and long usage affecting longevity and efficiency adversely.

2

A further object of the present invention is to provide a drawer operating mechanism, the principal components of which may be disposed behind shielding or paneling whereby to affect a minimum extent flush styling characteristics.

Further objects of the present invention are such as will become more evident during the course of the following detailed description as shall be understood from the hereunto appended claims.

Attention will now be directed to a specific description of a preferred embodiment of this invention. In the following specification and to the illustrations in the accompanying drawings like reference characters designate corresponding parts throughout.

Fig. 1 is a front elevational view of a steel cabinet structure such as may form a supporting base for a kitchen cabinet or oven;

Fig. 2 is a side elevational view of a portion of kitchen fixture similar to Fig. 1 showing an advanced condition of manual operation performed thereon;

Fig. 3 is a transverse sectional view taken approximately on line 3—3 of Fig. 1;

Fig. 4 is a view similar to Fig. 3 showing the operating mechanism which embodies certain features of the present invention in an advanced stage of operation;

Fig. 5 is a detailed elevational view of the same operating mechanism under somewhat reduced scale and may be identified by the locating arrows 5—5 on Fig. 3, and

Fig. 6 is a plan sectional view taken approximately on the line 6—6 of Fig. 3.

The principal cabinet chosen to illustrate this invention is of a type fabricated entirely of sheet steel and having side walls, one of which is visible in Fig. 2 and thereat indicated 11. The frontal wall of this apparatus which may be welded to or integrated with the side walls 11 is indicated 12 in Figs. 3 and 4 and is preferably provided with a lowermost inlet curvature as at 13 so that the housewife or kitchen attendant may be permitted to stand close to the table or other structure with the inlet curvature affording a nethermost clearance or toe recess.

The front panel 12 is provided variously with rectangular apertures usually constructed with inwardly turned flanges as at 14 having length and width dimensions suitable for receiving therethrough the container elements 15 of storage drawers. As best observed in Fig. 1, these container elements are provided with sidewardly extending parallel lip formations or flanges 16 that rest upon two or more spaced support rollers 17

pivotedly carried on horizontal brackets 18 riveted or welded to the side frames or to suitable internal partitions within the base of the cabinet.

Whether the drawers 15 are in this way or otherwise supported and guided is of secondary importance to the present invention, it being of primary significance to establish that for best results the movement of the drawer mechanisms should be attended with sufficient ease and freedom from frictional impairment to avoid any condition of binding or jamming such as might be consequent from the use of inert drawer supporting ledges.

Each drawer compartment 15 is provided with an escutcheon or face panel 21 to which it may be secured as by welding or riveting. This escutcheon may itself be shaped in a rectangular outline and obtains simulated thickness by being dished through a drawing process so as to present a planar surface edging 22 to impinge against the face of the frontal panel 12.

In this way the surface panels 21 are permitted to remain intact with their flush smooth lines unbroken by either recess or protruberance factors. A pusher arm 24 formed of a single length of wire rod is provided having oppositely out-turned pintles 25 that pass through circular apertures formed in the ear extensions 26 of a pivot bracket 27, see especially Fig. 5. The pusher arm 24 passes through a closely chambered rectangular aperture 28 in the frontal panel 12 at a point thereof which is effectively concealed from view at all times by the encompassing dimensions of the escutcheons 21.

Pivot brackets 27 may be given an additional quality of rigidity so as to be constructable of comparatively light sheet metal by being formed with lengthwise extending flutes or ribs 29. The lowermost extremities of the brackets 27 form pivot journals as at 31 by being appropriately shaped in semicylindrical fashion to encompass the transversely extending pivot rods or pins 32 shown to be solid members as in Figs. 3 and 4 or equally practical as a cotter pin device as shown in Fig. 5.

To the innermost surfaces of these brackets 27 there is integrated, preferably by welding, a composite foot bracket attachment made of two components, a major one 33 having a rigidifying formed rib 34 and being shaped with an acute angle whereby to afford the disposition shown in Fig. 3 during the retracted condition of the pusher or plunger 24, and a minor component 35 having an obtuse angle complimentary to that of the major bracket 33. The weld points whereby the components 33 and 35 are integrated to one another and with the bracket 27 are designated 36, Figs. 3 and 4.

Those portions of components 33 and 35 which after assembly become attached to the inner surfaces of the brackets 27, lie in a common plane and of these the extremity 38 of bracket 33 serves the additional purpose of closing or completing the journal encompassment of the pivot rod or pins 32.

In order to further journal the pivot element 32, the inlet curvature portions of the walls 12 are preferably stamp-sheared and struck out to provide pivot supporting ears 41, see particularly Fig. 1, although it will be understood that this support can be accomplished by other methods such as by surface-secured independent trunnion bracket fixtures having elements comparable with the ears 41 and similarly placed.

The horizontally extending portion of com-

ponents 33 and 35 may be permitted to protrude outwardly through a closely defining aperture 42 in the wall 13 and because the movement of the bracket 27 is pivotal with the horizontal portions 5 of members 33 and 35 closely approximating an arcuate path through the aperture 42 the interruption of this surface by reason of the aperture located in the inlet curvature wall 13 confines the esthetic variance to a minimum.

The outwardly extending portion of component 33 is bent to afford contiguous offsets designated 44, 45 and 46 of which offset facet 44 may be provided with a bumper stop 47 to rest on the floor surface when the mechanism is extended after the manner illustrated in Fig. 4. Offset facet 46 is perforated to permit the passage therethrough of mounting screws and to its inner surface there is attached a foot pedal molding 48 significantly profiled to present a curvature surface as at 49 preferably paralleling the filleted or dished shape of the escutcheons 21 and ribbed as at 51 to contribute traction during engagement by the attendant's operating toe, see also Fig. 6.

When the drawer is closed and the ejecting mechanism is fully retracted which is its condition shown in Fig. 3, curvature 49 closely defines the foregoing disclosed filleted surface of escutcheons 21 and also contributes towards retaining the drawers against any possibility of free rolling in a forward direction as during vibration or violent closing. During ajar or open condition of the drawer, the foot pedal and its integrally associated leverage mechanism drops below the drawer level so as to be aesthetically concealed from view and so as to be functionally clear of encounter.

While the present invention has been explained and described with reference to specifically contemplated forms and mechanical elements, it will be understood nevertheless that it is susceptible to moderate degrees of change and variation without departing from the essential spirit or scope thereof. Accordingly it is not intended to be limited to the illustrations which have been chosen in the accompanying drawings nor to the specific language employed in the foregoing description except as indicated in the hereunto appended claims.

The invention claimed is:

1. A foot operated mechanism for opening drawers comprising the combination with a horizontally slidable drawer having a frontal escutcheon overlapping in dimensions the perimeter outline of the forward portion of the drawer, of a treadle lever horizontally pivoted at a lowermost extremity on a pivot element, a pivoted plunger articulated to an uppermost extremity of said treadle lever and guided in linear motion against the inner surface of said escutcheon, and an arm integral with said treadle lever extending forwardly intermediate of its uppermost and lowermost extremities, said arm terminating with a foot pedal for engagement during operation, the said foot treadle being shaped to provide a curvature conforming with the outer contour of said escutcheon and when in retracted condition being disposed in the path of forward movement of said escutcheon to deter inadvertent opening of said drawer and escutcheon.
2. In a kitchen cabinet or similar device, a drawer receiving frontal panel having a rectangular opening through which there is permitted to move a rectangular storage drawer, said panel terminating at its lowermost level with receding curvature, a drawer supported for slidably move-

ment through said panel opening having at its foremost end a dished sheet metal escutcheon overlapping in dimensions the perimetric outline of the forward portion of said drawer, and an apparatus for opening said drawer by inward pressure against its said escutcheon comprising a horizontally pivoted foot treadle having an integral arm intermediate its extremities extending forwardly through an opening in the receding curvature portion of said frontal panel and terminating with a first angularly bent facet portion to which is secured a bumper and a final bent facet portion to which is secured a foot engagement portion, and a pusher pivotally carried by the uppermost extremity of said foot treadle and extending in a horizontal direction through an aperture in said frontal panel to exert a motion parallel to the movement of said drawer against the inner surface of its said escutcheon as said foot treadle is rotated correspondingly about its said horizontal pivot.

3. In a cabinet or the like comprising a base structure housing a horizontally shiftable drawer having a frontal escutcheon overlapping in dimensions the perimetric outline of the forward portion of the drawer, a treadle pivoted on a pivot element mounted on the internal surface of a frontal panel of said structure, a plunger articulated to an uppermost extremity of said treadle and passing through an opening of said frontal panel to engage the inner surface of said escutcheon, said treadle including an arm which passes through an opening of said frontal panel, said arm mounting at its extremity a protuberant molding shaped to provide a curvature conforming with the contour of said escutcheon and adapted, during the unoperated condition of said treadle, to be disposed in the path of forward movement of said drawer whereby to retain said drawer in its closed condition.

4. In a kitchen cabinet device, a base structure including a frontal panel having a rectangular opening through which there is received a storage drawer, said panel terminating at its lowermost level horizontally with a receding portion for af-

10 fording toe clearance, a drawer received in said opening having at its foremost end a face panel overlapping in dimensions the perimetric outline of the forward portion of said drawer, and a mechanism for opening said drawer comprising a horizontally pivoted treadle lever having a foot engaged operating arm extending through an opening in the receding portion of said frontal panel, and a pusher pivoted in the uppermost extremity of said lever and passing through an opening in said frontal panel which guides said pusher in a direction parallel to the movement of said drawer to push against the inner surface of said face panel, the terminal portion of said operating arm when the same is in non-operating condition being disposed in the path of forward movement of said drawer to deter inadvertent opening of said drawer.

20 5. In a cabinet or the like, the combination of a base structure including a frontal panel having a substantially rectangular opening through which is received a sliding drawer, said drawer having at its foremost end a face panel at least a portion of which overlaps a portion of the frontal panel adjacent said opening, a treadle lever horizontally pivoted at its lower end, a plunger pivotally connected to the upper end of said treadle lever and passing through a second opening in said frontal panel to engage the overlapping portion of said face panel, a forwardly extending arm integral with said lever intermediate its upper and lower ends, said arm terminating in a foot pedal which when in inoperative condition is disposed in the path of forward movement of said drawer to deter inadvertent opening thereof.
